UNITED STATES PATENT OFFICE.

GEORGE S. BLAKESLEE, OF CHICAGO, ILLINOIS.

WASHING MACHINE.

Application filed July 23, 1917. Serial No. 182,251.

To all whom it may concern:

Be it known that I, GEORGE S. BLAKESLEE, a citizen of the United States, and a resident of Chicago, in the county of Cook and State of Illinois, have invented certain new and useful Improvements in Washing Machines, of which the following is a specification, reference being had to the accompanying drawings.

10 My invention relates to washing machines intended for use in washing small articles of various kinds such as shells, castings, dishes, &c., and has to do with washing machines of that type in which the wash water, and also the rinsing water where rinsing is provided for, is arranged to be thrown against or upon the articles to be washed by means of paddle wheels or equivalent devices operating in a tank containing the 20 water, the articles to be washed being moved over the tank in such manner as to be subjected to the action of the water. One of the objects of my present invention is to provide a new and improved washing machine 25 in which the water is not only thrown violently up against the articles to be washed from below, but may be also directed downwardly upon the articles in large volume so that they are completely and effectually 30 cleansed. Another object is to provide a construction by which the water may be applied to the articles in a variety of ways, i. e. either in large volume or in the form of a spray or shower as may be preferred. 35 Other objects are to provide means for ensuring the separation of the wash water from the rinsing water and to provide improved means for holding the articles to be washed as they are passed through the machine so that such articles will not only be 40 properly supported during the washing operation, but also the proper manipulation of the water will not be interfered with by the containers in which the articles are carried. 45 I accomplish these objects as illustrated in the drawings and as hereinafter described. What I regard as new and desire to cover by this application is set forth in the claims.

In the accompanying drawings:
 50 Fig. 1 is a side elevation of my improved machine;
 Fig. 2 is a plan view thereof;
 Fig. 3 is a side elevation showing the op-

posite side of the machine from that shown in Fig. 1;

Fig. 4 is a longitudinal vertical section on line 4—4 of Fig. 2;

Fig. 5 is an enlarged partial longitudinal sectional view on line 5—5 of Fig. 6 illustrating the manner in which the water is 60 directed during the washing or rinsing operation;

Fig. 6 is a plan view of the parts shown in Fig. 5, the overhead deflector being omitted;

Fig. 7 is a plan view of one of the containers or baskets in which the articles to be washed are carried, certain parts being broken away;

Fig. 8 is a side elevation of one of the 70 baskets;

Fig. 9 is a vertical cross-section on line 9—9 of Fig. 7;

Figs. 10 and 11 are views illustrating two kinds of shells for the washing of which 75 the machine illustrated is more particularly intended.

Referring to the drawings, 12 indicates a tank of sheet iron or other suitable material which is oblong in shape and is divided by 80 a vertical partition 13 into a washing compartment 14 and a rinsing compartment 15. The tank 12 may be supported upon standards 16, or in any other suitable way. It is also provided with a hood 17 which extends over the entire tank and is open at its ends to permit the articles to be washed to be introduced at one end of the machine and discharged at the other. 18 indicates a tray or table at the inlet end of the 90 machine, and 19 a similar table at the discharge end, as shown in Fig. 2. 20 indicates rails, preferably made of angle iron, which extend longitudinally over the tank 12 adjacent to the opposite side walls of the 95 hood 17, as shown in Fig. 6. These rails serve to support the containers or baskets for the articles to be washed as they are moved along through the machine. 21—22 indicate baffle plates disposed about midway 100 of the washing and rinsing compartments 14—15, respectively, and extending from the upper portion of each of said compartments down to near the bottom thereof, as best shown in Fig. 4. These baffle plates 105 serve to keep the water in the compart-

55

65

100

105

ments 14—15 comparatively quiet and increase the efficiency of the water distributing means hereinafter described. 23—24 indicate paddle wheels in the end portions 5 of the washing and rinsing compartments, respectively. These paddle wheels are mounted on horizontal shafts 25—26, respectively, journaled in suitable bearings at the sides of the tank 12 so that the paddle 10 wheels extend transversely of their respective compartments. The shafts 25—26 are preferably placed about midway of the height of the tank 12 so that the wheels may be submerged to a greater or less extent by varying the depth of the water in the respective compartments. 27 indicates an overflow outlet pipe in the washing compartment 14, which is provided with an adjustable extension 28 by which the height 15 of the overflow may be regulated. A simple way of accomplishing this is by fitting the extension 28 on screw threads on the pipe 27. 29 indicates a similar overflow pipe in the rinsing compartment 15, and 30 a similar extension thereof. 31 indicates a discharge pipe with which the pipes 27 and 29 are connected. Said pipe may be provided with one or more valves if desired. Obviously by adjusting the extensions 28—30 the depth of the water in either the washing or the rinsing compartments may be regulated at pleasure.

32 indicates a guide or deflector disposed approximately vertically in the washing compartment 14 and extending transversely thereof adjacent to the paddle wheels 23 in such position that by the rotation of said paddle wheel the lower blades thereof throw the water upwardly and laterally against 35 said deflector. Said deflector is pivotally supported adjacent to its lower end upon a pivot 33 and its upper end is adjustably held in position by an adjusting rod 34 which passes through a plate 35 and 40 carries a wing nut 36, as shown in Fig. 4. Thus the inclination of the deflector 32 may be varied within rather wide limits. As shown in Fig. 4, the upper end of said deflector is slightly curved toward the 45 paddle wheel so that the water thrown up by the paddle wheel is directed to some extent over said wheel before it passes up, in the manner illustrated in Fig. 5. 37 indicates a similar deflector pivotally mounted at 38 in the rinsing compartment 15 and arranged to cooperate with the paddle wheel 24 in the same way that the deflector 32 cooperates with the paddle wheel 23. The deflector 37 is provided with an 50 adjusting rod 39 which passes through a plate 40 which carries a wing nut 41 so that the deflector may be readily adjusted. It will be noted that both the deflectors 32 and 37 are placed between their respective 55 paddle wheels and the adjacent overflow

pipes so that the agitation produced by the paddle wheels does not affect the overflow discharge.

42 indicates an overhead deflector disposed in the hood 17 over the paddle wheel 23 and partition 21. The deflector 42 is somewhat of the shape of a bow and is best made of sheet iron. One end portion of said deflector is provided with flanges 43 at its side edges by which it may be secured fixedly to the sides of the hood 17 in an inclined position, as shown in Fig. 4. The other end portion 42^a of said deflector is flexible and elastic and is not secured to the hood, but is free to be adjusted so that its curvature may be varied to vary the deflection of the water thrown against it. For the purpose of adjusting the part 42^a of said deflector, a rod 44 is provided, which is connected with the free or inner end 42^a of said deflector and passes through a suitable hole in the fixed or outer end of the deflector 42 where it is provided with a wing nut 45, as shown in Fig. 4. By screwing the wing nut 45 further up on the rod 44 the curvature of the part 42^a may be increased, and vice versa. It will be noted by an inspection of Figs. 4 and 5 that the inclined stationary portion of the deflector 42 overlies the paddle wheel 23, whereas the curved portion 42^a of said deflector overlies the washing compartment 14 at the left hand side of the baffle plate 21. The right hand end of the deflector 42 also is approximately in the same vertical plane as the vertical deflector 32 and consequently a considerable portion of the water thrown up by the paddle wheel 23 will be directed upward by the deflector 32 against the right hand end portion of the deflector 42, which will direct it laterally against the curved portion 42^a of the latter deflector so that it will ultimately be directed downward and into the left hand side of the compartment 14. Some of the water will of course be distributed by the paddle wheel 23 throughout the space between the baffle plate 21 and the deflector 32, as indicated by the arrows in Fig. 5, and that water also will be deflected by the overhead deflector 42 so that it passes down into the left hand side of the washing compartment 14, as indicated by the arrows in said figure. It will be apparent from the foregoing description that by adjusting the position of the deflector 32 and of the flexible portion 42^a of the deflector 42 the distribution of the water both in its upward and in its downward course may be varied within wide limits so that there may be either a wide distribution of the water in its upward course and a correspondingly wide distribution in its downward course, or the water may be thrown upward in a fairly compact volume and be returned in the same state. Furthermore by varying the level of the 130

water in the compartment 14, a still wider range of variation may be obtained. If the paddle wheel 23 is half submerged in the water the volume of water thrown upward will be more compact, whereas if the water level be lowered so that only the tips of the paddles dip into it the water will be thrown up in a spray, and within these limits an almost infinite variation of operation may be obtained. In order to ensure the separation of the wash water from the rinsing water a swinging curtain or shield 46 is provided, which is pivoted at 47 so as to hang down beyond the free end of the deflector 42 and bear against such end, as shown in Fig. 4. Preferably the lower end of said curtain is weighted, as shown at 48, and it hangs down far enough so that while it does not interfere with the passage of the containers hereinafter described it prevents splashing from one compartment to the other. Obviously, when the flexible portion 42^a is adjusted, the curtain 46 will automatically adjust itself so that it always remains in operative position. The rinsing end of the tank is provided with a similar overhead deflector 49 which corresponds in all respects with the deflector 42 except that it is set oppositely, as shown in Fig. 4. 49^a indicates the flexible portion of the deflector 49, 50 the flanges thereof, 51 the adjusting rod, 52 the wing nut, 53 the curtain, 54 the pivot of the curtain, and 55 the weight at the lower edge of said curtain. 56 indicates conveyor chains or belts mounted on sprocket wheels 57—58 carried by shafts 59—60, respectively, which extend transversely of the machine adjacent the inlet end thereof and slightly below the upper margin of the tank 12. Each belt 56 carries a lug 61 which is adapted to engage the receptacles or baskets in which the articles to be washed are placed, as will be hereinafter described, so that by the operation of said belts the baskets are pushed consecutively into the machine while resting on the tracks 20. The moving parts of the apparatus are all driven from an electric motor 62 preferably mounted on top of the hood 17, as shown in Fig. 3, and provided with a pulley 63 connected by a belt 64 with a pulley 65 mounted on the paddle wheel shaft 25 outside of the machine, as shown in Fig. 3. At its opposite end the shaft 25 carries a pulley 66 connected by a crossed belt 67 with a pulley 68 carried by the paddle wheel shaft 26, as shown in Fig. 1. The latter shaft carries at its opposite end a pulley 69 connected by a crossed belt 70 with a pulley 71 carried by a shaft 72 which is mounted on top of the hood 17 at the opposite end of the machine from the motor 62, as shown in Fig. 3. The shaft 72 carries a pinion 73 which meshes with a gear 74 mounted on a shaft 75 which car-

ries a sprocket wheel 76. Over the latter sprocket wheel runs a chain 77 which drives a sprocket wheel 78 mounted on the shaft 59, thus driving the basket moving chains 56. It will be apparent that the paddle wheels 23—24 are rotated in opposite directions.

The construction of the basket is best shown in Figs. 7, 8 and 9. It comprises upper and lower rectangular frames 79—80 connected by upright strips 81—82 at opposite sides thereof and having transverse rods 83' and 84 disposed intermediately. The uprights 82 are provided with laterally extending brackets 83 which serve as spacing devices to hold the consecutive baskets a proper distance apart, as illustrated in Fig. 5. The spacing apart of the baskets during the operation of the machine is an important feature of my invention, as I thereby provide spaces or passageways between consecutive baskets so that a considerable volume of water may pass up between them to be discharged downwardly upon their contents, as illustrated by the arrows in Fig. 5.

The bottom 85 of the basket is preferably of woven wire as shown in Fig. 9, but may be of any other suitable material or construction adapted to sustain the articles to be washed. The frames 83 and 84 carry longitudinal and transverse wires forming reticulated frames adapted to receive the articles to be washed and hold them in fixed position. Where the baskets are designed to carry shells, the shells are placed in them in an inverted position, the wires of the lower frame 84 engaging and holding the lower ends of the shells so that they are not disarranged by the impact of the water. Where the shells are of uniform diameter the spacing of the wires of the lower frame may be the same as in the upper frame, but where the ends of the shells are contracted, as shown in Fig. 10, the wires of the lower frame 84 are set closer together so that the squares formed are enough smaller to fit the reduced ends of the shells, as illustrated in Fig. 9. 87 indicates handles provided at the opposite sides of the basket.

As will be observed from an inspection of Fig. 5, which illustrates my improved machine as used for washing shells, the basket moving conveyor operates to move a basket into the machine to a point where it overlies the paddle wheel 23, the inner portion 120 of the basket stopping short of the baffle plate 13 by a space equal to the width of the frame or bracket 83. The lugs 61 act against the ends of the brackets 83 and consequently there is also a space between the sprocket wheel 57 and the adjacent end of the basket equal to the width of the bracket 83. The rotation of the paddle wheel throws the water up not only against the under side of the basket and into the open lower ends of

the shells, and up around the outsides of the shells, but also up through the spaces at the ends of the basket provided by the brackets 83 of consecutive baskets. After passing up 5 around the shells and at the ends of the basket the water is deflected by the overhead deflector and is thrown down upon the contents of the preceding basket which then overlies the left hand portion of the washing compartment, as illustrated in Fig. 5. The introduction of another basket moves 10 the preceding baskets along upon the tracks 20, the operation being repeated as fresh baskets are introduced into the machine. At 15 the rinsing end of the machine the same operation takes place, except that the baskets are first subjected to the down-flowing water and afterwards to the upwardly moving water thrown up by the paddle wheel 24.

20 It will be understood that while I have described with considerable particularity the embodiment of my invention illustrated in the drawings, I do not limit myself to the specific construction shown and described 25 except in so far as it is specifically claimed, as my invention includes generically the subject-matter of the broader claims.

What I claim as my invention and desire 30 to secure by Letters Patent, is

30 1. A washing machine comprising a tank, a hood extending thereover, a paddle wheel rotatably mounted in said tank, means for supporting the articles to be washed above said paddle wheel, a deflector cooperating 35 with said paddle wheel to direct the water thrown thereby upward into contact with the articles to be washed, and an overhead deflector in said hood overlying the articles to be washed and said paddle wheel and 40 serving to intercept the water thrown upward by the action of the paddle wheel and direct it downward into the tank.

2. A washing machine comprising a tank, a paddle wheel rotatably mounted therein, 45 means for supporting the articles to be washed above said paddle wheel, an approximately upright deflector pivotally mounted at its lower end portion in said tank, at one side of and adapted to cooperate with said paddle wheel to direct the water upward, and means connected with said deflector for 50 adjusting the position of the upper portion thereof, the upper portion of said deflector being curved toward the paddle wheel.

55 3. A washing machine comprising a tank, a hood extending thereover, means for supporting the articles to be washed over said tank, means in said tank for throwing water upward into contact with the articles to be washed, and a deflector disposed in said 60 hood over said water throwing means and above the articles to be washed and arranged to direct the water laterally and downwardly into the tank.

65 4. A washing machine comprising a tank,

means for supporting the articles to be washed over said tank, means in said tank for throwing water upward into contact with the articles to be washed, a deflector disposed over said water throwing means 70 and above the articles to be washed and arranged to direct the water laterally and downwardly into the tank, said deflector having a curved flexible portion, and means for adjusting the flexible portion of said deflector to vary its action in directing the movement of the water.

5. A washing machine comprising a tank, means for supporting the articles to be washed over said tank, means in said tank for throwing water upward into contact with the articles to be washed, an inclined deflector disposed over the articles to be washed above said water throwing means, 80 said deflector having a curved portion disposed at one side of said water throwing means whereby said deflector acts to direct the water laterally and downwardly into the tank, said curved portion being flexible and elastic whereby it may be adjusted independently of the inclined portion of said deflector.

6. A washing machine comprising a tank, a hood extending thereover, means for supporting the articles to be washed over said tank, means in said tank for throwing water upward into contact with the articles to be washed, an overhead deflector in said hood overlying said water throwing means and the articles to be washed, and a depending curtain adjacent to one end of said deflector.

7. A washing machine comprising a tank, a hood extending thereover, means for supporting the articles to be washed over said tank, means in said tank for throwing water upward into contact with the articles to be washed, an overhead deflector in said hood overlying said water throwing means and the articles to be washed, and a pivotally suspended curtain adjacent to one end of said deflector.

8. A washing machine comprising a tank, means for supporting the articles to be washed over said tank, means in said tank for throwing water upward into contact with the articles to be washed, an overhead deflector above said water throwing means and the articles to be washed, said deflector having a curved portion at one end, means for adjusting said curved portion of the deflector, and a curtain suspended adjacent to said curved portion of the deflector and automatically adjustable therewith to maintain its operative relation thereto.

9. A washing machine comprising a tank, means for supporting the articles to be washed over said tank, means in said tank for throwing water upward into contact with the articles to be washed, an overhead deflector above said water throwing means

- and the articles to be washed, said deflector having a curved portion at one end, means for adjusting said curved portion of the deflector, and a curtain suspended adjacent to 5 and bearing against the curved portion of said deflector whereby the adjustment of said deflector automatically adjusts the position of said curtain to maintain its operative relation with said deflector.
- 10 10. A washing machine comprising a tank, a paddle wheel in said tank adapted to throw water upward, means for supporting the articles to be washed above said paddle wheel, a deflector in said tank adapted to operate with said paddle wheel for directing water upwards, an overhead deflector above the articles to be washed and adapted to operate with said paddle wheel and said first-mentioned deflector, one or more receptacles adapted to contain the articles to be washed, a conveyor for moving said receptacles into washing position, and means for 15 spacing successive receptacles a distance apart to provide passageways for water at the ends of said receptacles.
- 15 11. A washing machine comprising a tank, a paddle wheel in said tank adapted to throw water upward, means for supporting the articles to be washed above said paddle wheel, a deflector in said tank adapted to 20 cooperate with said paddle wheel for directing water upwards, an overhead deflector above the articles to be washed and adapted to cooperate with said paddle wheel and said first-mentioned deflector, one or more receptacles adapted to contain the articles to be washed, a conveyor for moving said receptacles into washing position, and end brackets carried by said receptacles for spacing successive receptacles a distance apart to 25 provide passageways for water at the ends of said receptacles.
- 20

GEORGE S. BLAKESLEE.
